UNITED STATES PATENT OFFICE.

FREDERICK W. KING, OF CLEVELAND, OHIO.

ELECTRIC DRILL.

966,917.

Specification of Letters Patent. Patented Aug. 2, 1910.

Application filed December 15, 1909. Serial No. 533,195.

To all whom it may concern:

Be it known that I, FREDERICK W. KING, a citizen of the United States, residing at Cleveland, in the county of Cuyahoga and 5 State of Ohio, have invented a certain new and useful Improvement in Electric Drills, of which the following is a full, clear, and exact description.

This invention relates to drill presses of a kind well adapted for extremely light work such as that which is done by jewelers, opticians and others of like character.

The objects are to produce a vertically movable, electrically driven drill which may 10 be very cheaply made, effective in operation and occupy a very small space on the operator's table or bench, and one that shall have its electric motor counterbalanced and adapted to automatically close its own electric circuit to operate the motor at the beginning of 15 its movement, toward the work. These and other features of the invention, which will be referred to later on, are illustrated, in what is now considered a desirable form, by 20 25 the drawing in which:

Figure 1 is a view partly in elevation and partly in section. Fig. 2 is a side view of the lower portion of the same as seen from the direction of arrow 2 on Fig. 1. Fig. 3 30 is a transverse section through the base plate on the line 3—3 of Fig. 1. Fig. 4 is a transverse section on the line 4—4 of Fig. 1 of the guide frame upon which the motor slides and a portion of the motor engaged thereby.

35 The mechanism is mounted upon and carried by a base plate A, preferably formed with depending side flanges a, and upon it is mounted a rotatable chucking device B adapted to hold lenses or similar fine work 40 to be drilled. This chuck with its various slides and adjustments are not considered new with this invention as they are now to be found upon open market.

At one side of the base plate is secured a 45 standard C provided at its upper end with channel guideways D, D in which is mounted a sliding head or block E to which is rigidly secured an electric motor F of any preferred construction adapted to this position. The motor spindle or driving shaft G 50 extends out of its lower end and carries a chuck H in which may be secured a drill or other desired tool I. The motor and work chuck are in axial alinement and the motor 55 adapted to move up and down in order to

bring its tool into operation upon the work secured by the chuck.

Rigidly attached to the sliding motor head E is a vertical rod J provided with an adjusting collar K and passing through the 60 top of the base plate A, as shown, with a spring L surrounding it between the collar and base plate. The office of this spring is to overbalance the weight of the motor, lifting and holding it clear above and away 65 from the work in the chuck. On the lower end of this rod and inside of the base plate is secured a collar M which is acted upon by a lever N secured upon one end of a rock shaft O mounted in suitable bearings in the 70 base plate and provided at its projecting extremity with a lever P by means of which the operator may draw down the motor and drill against the lifting stress of spring L.

On the outer side of the base and extending into the path of the operating lever P is a gage screw W which may be set to limit the throw of the lever as desired.

Secured to the lower face of the collar M 75 is a contact spring Q which, when the motor is lowered, comes into spring contact with an opposing spring R secured to but insulated from the base, as shown at S in Fig. 3.

The electric circuit is diagrammatically shown in Fig. 1 where the line-wire T extends from battery U to the motor wires at V; thence through the motor windings from which they are grounded on the metallic frame leading to and through the rod J to spring Q and thence, when in contact, 85 to spring R and by line T' back to battery.

In the commercial operation of these drills sufficient electric energy may be derived from small dry cell batteries,—two of 90 which are usually enough to give the required power although a greater number may be employed if deemed necessary.

In operation the piece of work to be operated upon is suitably placed in the chuck B and then by means of the lever P operating through shaft O, lever N and rod J, the motor is drawn down to the work, the electric circuit being closed at Q R at the first stage of this movement and the motor set 100 into rotary action thereby. On the completion of the operation the lever P is released and the motor raised to its normal position of rest by the spring L, the circuit being broken on the separation of contacts Q R. 105 By means of this arrangement electric cur- 110

rent is used only when the drill is operating upon the work, thereby preventing any waste battery power as might occur with ordinary switches that the operator might 5 fail to open, either to save trouble between different operations or through forgetfulness.

The production of a drill press of this kind that may be operated with current produced by ordinary dry cell batteries is a 10 commercially valuable invention. In large cities and at places where central power plants produce current for sale the power for running a drill of this character might 15 be bought from such producer, but in small country villages and towns jewelers and others having use for such light drills may obtain dry cell batteries and be entirely independent of any power plants.

20 This device is shown as arranged particularly for drilling purposes but other than drilling tools might be held in the tool chuck on the motor spindle and perform other operations and this is considered to be within 25 the province of the invention.

Having described my invention, I claim:

1. In a drilling machine, the combination of an electric motor adapted to operate a tool and be longitudinally movable on the line of 30 its axis, an electric circuit including the motor, a switch in said circuit normally open when the motor is in normal position most retracted from its work, with means whereby said switch is automatically closed upon 35 the movement of said motor toward its work.

2. In a drilling machine, the combination of an electric motor adapted to operate a tool and be longitudinally movable on the line of its axis, means for retracting and 40 yieldingly holding the motor away from its work, an electric circuit including the motor, a switch in said circuit normally open when the motor is in retracted position, with means for automatically closing said switch upon 45 the movement of the motor toward its work.

3. In a drilling machine, the combination of a base, a work chuck mounted thereon, a vertical guide post extending from the base, an electric motor movably mounted on said 50 guide post and adapted to operate a tool, a spring adapted to retract and yieldingly hold the motor away from the work chuck, with means for moving the motor against the pressure of said spring, an electric circuit 55 including the motor, a switch in said circuit and a member actuated by the motor-

moving mechanism to contact with said switch and close the circuit and start the motor into rotation.

4. In a drilling machine, the combination 60 of a base, a work chuck mounted thereon, a vertical guide post extending from the base, an electric motor movably mounted on said guide post and adapted through its spindle to operate a tool, a rod connected to the motor and depending therefrom through the 65 top of the base, an adjusting collar on said rod and a spring embracing the rod between said collar and the base with an electric circuit including said motor.

5. In a drilling machine, the combination 70 of a hollow base, a vertical guide post extending from the base, an electric motor movably mounted on said guide post and adapted to operate a tool, a rod connected to 75 the motor and depending therefrom through the top of the base, an adjusting collar on said rod and a spring embracing the rod between said collar and the base, a collar on the end of the rod inside of the base, a lever 80 engaging said collar, a rock shaft mounted in bearings in the base and supporting said lever, with a hand lever mounted on said rock shaft outside of the base, and an electric circuit including the motor.

6. In a drilling machine, the combination 85 of a hollow base, a vertical guide post extending from the base, an electric motor movably mounted on said guide post and adapted to drive a work tool, a rod connected to the motor and depending therefrom through the top of the base, an adjusting collar on said rod and a spring embracing the rod between said collar and the base, a collar on the end of said rod and a contact on the rod, inside of the base, a lever 90 engaging said collar, a rock shaft supporting said lever and mounted in bearings in the base, a hand lever on said shaft outside of the base, with an electric circuit including the 95 motor and having a spring switch member having insulated support on the base with its free end lying in the path of the contact on said rod which is in ground circuit from the motor.

In testimony whereof, I hereunto affix my signature in the presence of two witnesses.

FREDERICK W. KING.
